UNITED STATES PATENT OFFICE

WILLIAM J. DENNIS, OF CHICAGO, ILLINOIS

METAL WEATHER STRIPPING

Application filed August 4, 1927. Serial No. 210,693.

My invention belongs to that general class of devices known as weather stripping or the like and relates more particularly to a weather stripping constructed of spring metal or the like which will have a considerable resiliency. The invention has among its objects the production of a weather stripping of the kind described that is simple, inexpensive, efficient, durable, reliable and satisfactory for use wherever found applicable. More especially it has as an object the production of an efficient weather stripping or sealing strip between two relatively sliding parts such as, for example, a sliding sash, same being arranged between the edge of the sash and sash frame or window jamb. It has among its other objects the production of a stripping of the kind described which will not only effectively form a seal between the sliding parts, thereby shutting out cold winds, rain, dust and dirt, but which will tend to prevent chattering of the window sash, as well as tend to cause the same to run true in the window frame. The same may be installed either in new work or in old constructions without requiring the removal of the sash or sliding part, and when once installed fits itself to the particular installation. Many other objects and advantages of the method and construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a sectional view through a portion of a window sash frame or window jamb, with my improved weather stripping applied thereto; and

Fig. 2 is a perspective view of a strip of the weather stripping enlarged to more particularly show the construction and form before installation.

Referring to the drawings, in which a preferred embodiment is shown, the weather

stripping consists of a strip of metal, preferably spring metal, that will not corrode and of suitable gauge to have the desired degree of resiliency. In the strip shown, the same is formed with what may be termed a tacking flange or edge 1. Then it is bent away from the plane of the flange 1 as indicated at 2, and thence bent over again as indicated at 3, and thence more or less parallel with the flange 1 as indicated at 4—6, thence bent over again as indicated at 7, and back as indicated at 8, and thence more or less parallel in the same plane as the flange 1 to provide an edge flange 9 at the opposite side of the strip. The bends at 3 and 7 form substantially beads and are preferably more or less rounded as shown so as to project beyond the portion 4—6 between the two side flanges. At a desired point intermediate the beads 3 and 7 there is provided a bead 5 which I prefer to form with a substantially sharp bend or angle at the outer face portion and which is of a height to project beyond or above the rounded beads 3 and 7. While the beads 3 and 7 may themselves be sharper than shown, these are generally made rounded, the degree of the rounding depending upon the size of the strip, the gauge of the metal, etc.

At the juncture of the flange 1 and portion 2 and flange 9 and portion 8, it is generally preferred to slightly round the strip as indicated at 10 and 11. As shown in Fig. 2, the outer edges of the flanges 1 and 9 are bent slightly laterally. It has been found in applying weather stripping of this character that there is a tendency for the edges of the flanges, particularly the edge of the secured flange, to turn upward. This tendency to turn upward is due to some extent to the pressure exerted by the heads of the nails, tacks, screws or other securing devices, as well as pressure exerted on the flanges from other sources. By forming the edges of the flanges as shown in Fig. 2, this difficulty is overcome and a perfect seal obtained. The weather stripping when applied assumes the form shown in Fig. 1.

In Fig. 1 I have illustrated a window frame or jamb 15 and a window sash 16, 17 being the usual stops. In the space between

the edge of the sash and the frame is positioned the weather strip, the same being suitably secured to one of the parts, for example, as shown to the jamb 15 by means of 5 tacks 18 or equivalent means for the purpose.

When the weather strip is first applied, it 10 may tend to more or less flatten out, the pointed bead 5 will be in engagement with the sash 16. Depending upon the thickness of the metal in the strip, the beads 3 and 5 may or may not be in contact with the sash or one or the other may not. If the gauge 15 of the metal is such that the portions 4 and 6 are depressed, all three may be in contact. This, however, is more or less immaterial. After the strip has been in use for a short period of time, the bead 5 tends to wear or form a groove 19 in the sash 16 so that the heads 3 and 7 are in contact with the 20 sash edge with the bead 5 in its formed groove 19. Obviously, a perfect seal is secured, preventing the passage of wind, rain, dust or dirt or foreign material between the sash and its frame. The engagement with the 25 sash in the manner described tends to prevent chattering or vibration of the sash, the weather stripping yieldingly holding the sash against undue vibration. The sash runs easy on the strip.

30 It will be particularly noted that this type of weather stripping may be installed in old work without removing the sash from the frame, and should it be required may be removed or renewed in the same manner. It 35 is unnecessary to remove the sash for groove 19 to be formed, same being formed by bead 5 after the installation. On new work, a slight groove or saw-kerf may be formed in the sash in which the groove forming angle 40 is located, serving as a guide for the same and aiding in the formation of the complete groove by use. The sash is always maintained in proper position between the stops and as a result will always run true.

45 Having thus described my invention, it is obvious that various immaterial modifications may be made in the same without departing from the spirit of my invention; hence I do not wish to be understood as 50 limiting myself to the exact form, construction, arrangement and combination of parts herein shown and described or uses mentioned.

What I claim as new and desire to secure 55 by Letters Patent is:

1. A weather stripping of the character described including a longitudinally extending marginal portion, an oppositely arranged longitudinally extending marginal portion, and an intermediate portion connecting the said two marginal portions, said intermediate portion having a groove forming bead.

2. A weather stripping of the character described comprising a longitudinally extending marginal portion adapted to be se-

cured to a frame, an oppositely arranged longitudinally extending marginal portion arranged for sliding engagement with the frame in the same plane as that in which said first-mentioned marginal portion is adapted to be secured, and an intermediate portion connecting the said two marginal portions, said intermediate portion having a plurality of beads one of which is V-shaped adapted to seat in a cooperating part.

3. A weather stripping of substantially resilient material including a longitudinally extending marginal portion, said marginal portion having its extreme outer edge bent downwardly at an angle and an upwardly and outwardly extending portion containing a groove forming bead.

4. A weather stripping of the character described comprising a longitudinally extending portion adapted to be secured to one of two cooperating parts, said portion having its extreme outer edge bent downwardly at an acute angle, and an upwardly extending portion at the inner edge having a plurality of beads, one of which is adapted to form a groove in the other cooperating part.

5. A weather stripping of the character described including a marginal portion, said marginal portion having its extreme outer edge bent downwardly at an angle, an oppositely arranged marginal portion, and an outwardly bulging connecting portion having a groove forming bead.

6. A weather stripping of the character described comprising a longitudinally extending marginal portion, said marginal portion having its extreme outer edge bent downwardly, an oppositely arranged longitudinally extending marginal portion with its extreme outer edge bent downwardly, and a connecting portion outwardly extending intermediate its ends and having a plurality of beads, one of which is groove forming.

7. A weather stripping of the character described including a longitudinally extending marginal portion adapted to be secured to the frame, an oppositely arranged marginal portion in approximately the same plane as the first named marginal portion when the device is installed in the frame, and an outwardly extending connecting portion having a groove forming head.

8. A weather stripping of the character described comprising a longitudinally extending portion secured to the frame, an oppositely arranged similar portion in approximately the same plane as the first named portion when the device is installed, said second named portion in sliding engagement with the frame, and a connecting portion outwardly extending intermediate its ends formed of resilient material with a plurality of beads, said beads adapted to engage a substantially plane surface when under com-

pression by said surface, one bead being groove forming and under greater tension when said beads engage said surface.

9. In combination, two relatively slidable members, a device inserted therebetween comprising a marginal portion secured to one of the members, an oppositely arranged marginal portion in sliding engagement with said member, and a connecting portion for 10 said marginal portions, said connecting portion in engagement with the other relatively slidable member and having a groove forming bead.

10. In combination, two relatively slidable members, a device inserted therebetween including a marginal portion secured to one of the members, a second marginal portion opposite said first named marginal portion in engagement with said member, and a connecting portion for 15 said marginal portions extending outward toward and engaging the other relatively slidable members, said connecting portion having a plurality of beads engaging said second relatively slidable 20 member, one of said beads being groove forming.

11. A weather stripping of the character described including two substantially flat marginal portions with an intermediate portion 25 connecting the said two marginal portions and provided with a bead intermediate the said marginal portions, each of said marginal portions having the extreme edges bent laterally in a direction opposite to the 30 projection of the bead.

In testimony whereof, I have hereunto signed my name.

WILLIAM J. DENNIS.
